F. A. COFFIN.
CABINET DESK.

D. 18,112.

Patented Feb. 28, 1888.

FIG. 1.

FIG. 2.

UNITED STATES PATENT OFFICE.

FRANCIS A. COFFIN, OF INDIANAPOLIS, INDIANA.

DESIGN FOR A CABINET-DESK.

SPECIFICATION forming part of Design No. 18,112, dated February 28, 1888.

Application filed December 15, 1887. Serial No. 258,038. Term of patent 7 years.

To all whom it may concern:

Be it known that I, FRANCIS A. COFFIN, of Indianapolis, county of Marion, and State of Indiana, have invented a certain new and 5 original Design for Cabinet-Desks; and I do hereby declare that the following is a full, clear, and exact description thereof, reference being had to the accompanying engravings, which illustrate the same.

10 My invention consists in a new design for cabinet writing-desks, and will be understood from the following description.

In the engravings illustrating the specification, Figure 1 represents a perspective view of 15 the desk closed up. Fig. 2 is a similar view with the flexible curtain thrown back, showing the interior arrangement of the cabinet, the cupboard-door open, and the drawers open a little way.

20 In detail, the desk comprises a table carrying a cabinet-top, which is closed by a flexible curtain in the usual manner, and a frame-work composed of a couple of pedestals, one on each side of the central space. The top is of medium of height and incloses a row of pigeon-holes at the top for papers and letters, two longer compartments below for small books or writing-paper, and two small drawers beneath these. Between these drawers and below 25 them is an open space. The edges of the table-top are molded and project beyond the framework on the front side and ends. One of the pedestals contains a series of drawers increasing in width from the top to the bottom, and 30 the other a single drawer above and a cupboard containing pigeon-holes and partitions for books and papers, which is closed by a door. The drawer-fronts are ornamented with pairs

of straight lines above and below the handles, which are of a molded pattern, hollowed out 40 beneath for the insertion of the fingers. The drawers, when closed, go in flush with the front, and the edges are plain. The corners of the pedestals are finished with flat molded pilasters having plain bases and molded capitals. Between the pedestals is a central open space. The finish upon the drawer-fronts, consisting of two parallel lines, is carried out upon the bases of the pedestals and the bracket-strip between them and beneath the table-top. 45

The leading features of my design are in the details hereinbefore indicated.

I claim—

The design for cabinet-desks herein shown, comprising a base consisting of two pedestals, 55 one inclosing a set of drawers of different widths, the other a drawer and cupboard below closable by a door, a cabinet-top of medium height resting upon a table, its sides paneled, their upper edges formed with a 60 double groove and molded, as shown, its interior arranged with a row of pigeon-holes, two longer partitions, and a pair of small drawers closable by a folding curtain, the drawers having molded handles and their fronts ornamented with pairs of straight lines, the corners of the pedestals finished with flat molded pilasters having plain bases and molded capitals, substantially as shown and described. 65

In witness whereof I have hereunto set my 70 hand this 2d day of November, 1887.

FRANCIS A. COFFIN.
